UNITED STATES PATENT OFFICE.

CHARLES L. BETTS, OF NEW YORK, N. Y., ASSIGNOR TO R. E. DIETZ COMPANY, OF NEW YORK, N. Y.

HEADLIGHT.

No. 927,768.

Specification of Letters Patent.

Patented July 13, 1909.

Application filed April 23, 1908. Serial No. 428,863.

To all whom it may concern:

Be it known that I, CHARLES L. BETTS, a citizen of the United States, residing at New York, borough of Brooklyn, in the county of 5 Kings and State of New York, have invented a new and useful Improvement in Headlights, of which the following is a specification.

This invention relates to that class of headlights which are used on vehicles, particularly automobiles, and has for its object to provide such headlights with means for quickly and conveniently changing the forward reflection of light so that the full reflecting power can be had when required, for 10 instance, when running on a dark road, while the reflection can be quickly diminished when running on a lighted street, where the full reflection is objectionable by reason of the blinding glare.

20 In the accompanying drawings: Figure 1 is a rear elevation partly in section in line 1—1, Fig. 2. Fig. 2 is a longitudinal section showing the rear reflector in its normal position. Fig. 3 is a sectional elevation showing 25 the rear reflector tilted. Fig. 4 is a fragmentary longitudinal section of the lower portion of the rear reflector and connecting parts, on an enlarged scale. Fig. 5 is a vertical transverse section on line 5—5, Fig. 4.

30 Like reference characters refer to like parts in the several figures.

A represents the shell or casing of the headlight which may be of any desired form and which is shown as comprising a horizontal 35 cylindrical body 10, a flaring front 11 and a closed back 12.

13 represents an acetylene burner or other suitable source of light arranged within the body 10 of the shell in any suitable manner. 40 14 represents the front glass or lens and 15 the front reflector secured within the front portion of the shell and having the form of a forwardly flaring truncated cone.

B represents the rear reflector arranged 45 within the rear portion of the shell and comprising a shallow concave glass reflector 16 and an annular metallic frame 17 in which the glass is secured. This reflector is suspended within the shell by means of a trans-

verse hinge or pivotal joint 18 which is arranged at the top of the reflector and on which the latter can be adjusted with a forward or backward pendulous movement, so that the reflector can be placed either in its normal upright position, represented in 50 Fig. 2, or obliquely, as represented in Fig. 3. In the normal position the optical axis of the rear reflector coincides with that of the fixed front reflector 15, while in the oblique position the axis of the rear reflector is deflected downwardly.

The rear reflector is provided at its lower end with a threaded screw stem 19 which extends downwardly through a longitudinal slot 20 in the shell and which is provided with a screw nut 21 which can be tightened against the under side of the shell for securing the reflector in its adjusted position. The rearward movement of the reflector may be limited by a stop 22 secured in the shell. 70 Upon releasing the screw nut the reflector can be shifted from one position to another and when the reflector has been shifted it is readily secured in the desired position by tightening the nut.

75 In the normal position of the movable rear reflector its optical axis is in line with the optical axis of the fixed front reflector and a powerful forward reflection is secured, which is resorted to when necessary, as for instance, 80 when running on an unlighted road. Upon tilting the rear reflector, the latter is rendered ineffective to a large extent and the forward illumination is furnished mainly by the direct light of the flame or other source 85 of light and the front reflector, which illumination is sufficient for running on lighted streets or roads. Either the full forward illumination or the partial illumination can be quickly secured by means of the adjusting 90 mechanism under control of the driver.

I claim as my invention:

1. The combination with a headlight casing and a source of light arranged therein, of a movable reflector hinged at one end to 95 swing forwardly and backwardly at the opposite free end, a stem extending from the free end of the reflector through the casing,

and means on the outer side of the casing for securing the stem in position, substantially as set forth.

2. The combination with a headlight casing having a longitudinal slot, and a source of light arranged in said casing, of a movable reflector supported at the top by a transverse hinge and provided at the lower end with a screw stem which projects through said slot

and is provided on the under side of the casing with a clamp nut, substantially as set forth.

Witness my hand in the presence of two subscribing witnesses.

CHARLES L. BETTS.
